(No Model.)

O. H. WOODWORTH.
CHRONOSPHYGMOMETER.

No. 576,180.

Patented Feb. 2, 1897.

UNITED STATES PATENT OFFICE.

ORSON H. WOODWORTH, OF INDIANAPOLIS, INDIANA.

CHRONOSPHYGMOMETER.

SPECIFICATION forming part of Letters Patent No. 576,180, dated February 2, 1897.

Application filed April 10, 1896. Serial No. 587,048. (No model.)

To all whom it may concern:

Be it known that I, ORSON H. WOODWORTH, a citizen of the United States, residing at Indianapolis, in the county of Marion and State 5 of Indiana, have invented certain new and useful Improvements in Chronosphygmometers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to improved devices and mechanism for timing and enumerating the movements of the human pulse or the beats or pulsations of any pulsatory body.

A leading characteristic of this invention 20 is its effective adaptation to practical use in connected attachment to and combination with the running and timing movements of a watch of the size, character, and construction usually carried by practicing physicians and 25 surgeons.

The general objects and nature of my invention are set forth in this specification and accompanying drawings, in which similar letters and figures of reference indicate corresponding parts throughout the several views.

In the drawings, Figure 1 is a general plan view of the operative parts of the invention shown in connection and combination with portions of the running movements of a watch.

35 Fig. 2 is an enlarged representation of the acicula or pulse-timing needle and the various devices directly employed to actuate said acicula. Fig. 3 shows a central sectional view on line *x y* of the watch and especially 40 its upper plate *C* and inner case or cap *B* as they are employed in combination with the acicula; and Fig. 4 represents the watch with the acicula-tube *L* extending outwardly through aperture *N* in cap *B* and the point 45 of the acicula *K K* slightly protruding from the outer end of said tube.

50 My improved chronosphygmometer is especially designed and adapted for the use and convenience of physicians and surgeons in taking their patients' circulation, which object by the use of this invention they are enabled to readily and correctly accomplish

entirely by their sense of feeling and without being required to employ their sense of sight or hearing. Thus by the use of my improved 55 instrument any patient's circulation can be taken in the dark more conveniently and accurately than it can be done by daylight or any artificial light under the ordinary method heretofore employed. 60

Referring in detail to the drawings, *A* is the outer case of the watch. *B* is the ordinary inner cap of said case.

C is the upper, and *D* the lower plate, between and by which the running movements 65 of the watch are held in position.

*D*² is the dial, and *D*³ the glass or crystal.

E is the center wheel, *F* the third wheel, and *G* the second wheel of the watch.

H represents an annular disk or auxiliary 70 wheel attached to and carried by third wheel *F*, said disk being riveted or otherwise securely fastened to said third wheel, as at 13. Said disk is provided with actuating-studs *J J*, formed integrally therewith or attached 75 thereto and adapted to engage with and actuate arm *K*² of the lever *K*, pivoted in eyes *e*, secured on the plate *C*, and thus impart motion to arm *K*³ and through it also actuate the pulse-timing needle *K K*, carried thereon and 80 extending outward through acicula-tube *L*.

S is the acicula-spring, firmly attached to spring-setting arm *9*, which is jointed to setting-block *M*, said spring *S* constantly bearing upward on arm *K*³, carrying the acicula 85 *K K*. Stud 11 is firmly affixed to block *M* and adapted to receive set-screw 12 to regulate the pressure of spring *S* on arm *K*³.

Actuating-studs *J J* are so formed as to extend upward at right angles from the outer 90 edge of the upper face of the disk *H* as far as desired, and are then deflected at right angles and extend outward parallel with the direction of the cogs of wheel *F* and toward the periphery of said wheel as far as practicable 95 without interfering with the pinion 16 of the second wheel *G*. Just enough actuating-studs are provided on disk *H* to cause one upward and outward thrust of the acicula or needle *K K* each half-minute by means of the successive engagements of said studs with arm *K*² as wheel *F* and disk *H* conjointly revolve with the ordinary running of the watch. 100

The practical operation of my improved

chronosphygmometer is substantially as follows: The watch to which and with which my invention is attached and combined being wound up, running, and keeping time, the 5 wheel F rotates as per arrow a, and the actuating-studs J J of disk II, attached to and carried by said wheel, successively engage with arm K² by means of connecting-rod K, which is jointed to upper plate C by suitable joints or eyes e 10, e and may be of any desired length and size to suit its location and connection with arms K² and K³. Arm K² extends downward from its right-angled junction with rod K to its successive operable engagements with said 15 studs J J. At each of said engagements a stud J of disk II presses arm K² aside, slightly rotates connecting-rod K in joints or eyes e e, depresses arm K³ to dotted lines 15, and thereby withdraws the acicula downward in 20 its tube L, and these movements of the parts mentioned are continued until the actuating-stud then pressing against the lower part of arm K² passes beyond said arm's extreme lower point, whereupon the constant upward 25 pressure of acicula-spring 8 in notch 7 on the under side of arm K³ instantly stops and reverses the motion of arm K² and forces it immediately back to its former position at the dotted lines 14, and arm K³ is also simultaneously forced upward against the under side 30 of plate C from its former position at the dotted lines 15, and at the same moment the acicula K K, carried by said arm, is by said pressure thrust upward through its tube L, 35 with its extreme point slightly projecting outward through said tube. This extreme point of the acicula is made sufficiently sharp so that when it is thrust upward and outward through tube L in the manner described and 40 under a normal pressure of the acicula-spring 8 said point will slightly penetrate a finger or thumb gently pressed over the outer open end of tube L, which extends outwardly through the aperture N in cap B and flush 45 with the outer surface of said cap.

It is evident that if the pressure of acicula-spring 8 in notch 7 of arm K³ is too strong it will retard the free running of the watch and if said pressure is too weak the outward 50 thrusts of the acicula-point will not sufficiently penetrate the thumb or finger of the practitioner when using the chronosphygmometer in taking a patient's circulation. Therefore to most effectively regulate the 55 pressure of said spring the setting-block M is attached to or inserted in the upper plate C of the watch, the spring-setting arm 9 is jointed at 10 to said block, stud 11 is rigidly affixed thereto, and set-screw 12 is fitted to 60 operate in and through said stud and against arm 9, which has one end of the acicula-spring 8 attached firmly thereto, as shown. With the seven elements last mentioned—viz., the block M, plate C, spring-setting arm 9, stud 65 11, set-screw 12, and the acicula-spring 8—all arranged and attached as indicated it is plainly apparent that screwing set-screw 12

inward against spring-setting arm 9 will effectively increase the pressure of spring 8 on arm K³ and screwing said set-screw outward 70 will effectively decrease said pressure, as may be desired.

In the practical use of my improved chronosphygmometer the physician or surgeon takes in his hand the combined instrument, 75 which outwardly resembles an ordinary watch, and holding it in any convenient manner so that a thumb or finger gently presses on the cap B over the outer end of tube L and the acicula-point therein he will soon feel the 80 light thrusts of the acicula-point repeated every half-minute with the utmost regularity. Then to take a patient's circulation he has only to hold the instrument as above indicated, apply to the patient's pulse the fingers 85 of the same hand with which he holds the instrument or those of the other hand, and count the pulsations from the instant he feels a thrust of the acicula-point until he feels the next thrust or as many more as desired, the 90 thrusts occurring precisely one-half minute apart or at the uniform rate of exactly two thrusts per minute. By thus using the invention the pulsations may be readily and accurately timed and enumerated in the dark, 95 even if the practitioner should, unfortunately, become entirely deaf and blind.

The actuating-studs J J may be inserted in the upper surfaces of wheels F when said wheels are being manufactured, but I prefer 100 to attach to said wheel the disks II, with their actuating-studs already formed thereon, because such disks can readily be so attached after the watches to which said wheels belong have been running several years, and when 105 so attached the other changes required in the plate, cap, or other parts of the watch can then be made, and thus a watch and the distinctive features of this invention may be combined and unified after the watch has 110 been used several years or when the combined chronosphygmometer is being manufactured, as may be desired. Plate C is shown largely 115 cut away to exhibit operative parts of the invention, and plate D and cap B are thus cut away for the same purpose.

Arm K², rod K, arm K³, and the acicula K K are all continuously connected in one entire piece at the right angles 3 4 5 and the 120 lengths of the parts named between the angles 3 and 4 and 4 and 5 depend on the dimensions of the watch to which they are applied.

What I claim as my invention, and desire to secure by Letters Patent of the United States, is—

1. In a sphygmometric watch, the combination of a watch-movement, an apertured easing therefor, a series of tripping devices carried by a wheel in the train of the movement, and a lever pivotally secured to a plate of said movement, and having one arm engaged in succession by said tripping devices, said lever carrying a needle projecting through said aperture, substantially as described.

2. In a sphygmometric watch, the combination of a watch-movement, an apertured cap of the casing thereof, a lever pivotally secured to a plate of said movement, the same comprising an axis mounted in bearings on said plate, a long arm extending substantially at right angles to said axis and parallel to said plate, and a short arm extending outward from said axis, a series of tripping devices mounted on a wheel in the train of the watch-movement, and adapted to engage the short arm, and a needle carried by the long arm and projecting through said aperture, substantially as described.

15 3. In a sphygmometric watch, the combination of a watch-movement, an apertured casing therefor, a lever pivotally secured to a plate of said movement and carrying a needle projecting through said aperture, an auxiliary wheel mounted on a wheel in the train of the watch-movement, and a series of tripping devices, each provided with a radially-extending trip-finger adapted to engage an arm of said lever, and actuate said needle, substantially as described.

20 4. In a sphygmometric watch, the combination of a watch-movement, an apertured inner casing therefor, a plate, as C, correspondingly apertured, and a needle-tube extending between said apertures, a series of tripping devices carried by a wheel in the train of the watch-movement, and a lever pivotally secured on a plate of the watch-movement, and having one arm engaged in succession by said tripping devices, said lever carrying a needle reciprocable in said needle-tube, substantially as described.

25 5. In a sphygmometric watch, the combination of a watch-movement, an apertured casing therefor, a series of tripping devices carried by a wheel in the train of the movement, a lever pivotally secured on a plate of the movement, and having one arm engaged in succession by said tripping devices, said lever projecting through said aperture, and a spring actuating said lever to project said needle, substantially as described.

30 6. In a sphygmometric watch, the combination of a watch-movement, an apertured inner cap of the casing thereof, a lever pivotally secured to a plate of the movement, said lever comprising an axis mounted in bearings on said plate, a long arm extending substantially at right angles to said axis and parallel to said plate, and a short arm extending outward from said axis, a series of tripping devices mounted on a wheel in the train of the watch-movement, and adapted to engage the short arm, a needle carried by the long arm and projecting through said aperture, and a spring actuating said lever to project said needle, substantially as described.

35 7. In a sphygmometric watch, the combination of a watch-movement, an apertured casing therefor, a lever pivotally secured on the watch-movement, and carrying a needle pro-

jecting through said aperture, an auxiliary wheel mounted on a wheel in the train of the watch-movement, a series of tripping devices, each provided with a radially-extending trip-finger adapted to engage an arm of said lever and withdraw said needle and a spring for projecting said needle, substantially as described.

40 8. In a sphygmometric watch, the combination of a watch-movement, an apertured inner casing therefor, a plate B, correspondingly apertured, and a needle-tube extending between said apertures, a series of tripping devices carried by a wheel in the train of the watch-movement, a lever pivotally secured on a plate of said movement, and having an arm engaged in succession by said tripping devices, said lever carrying a needle reciprocable in said needle-tube, and a spring projecting said needle, substantially as described.

45 9. In a sphygmometric watch, the combination of a watch-movement, a series of tripping devices carried by a wheel in the train of the movement, a lever pivotally secured on a plate of said movement, and having one arm engaged in succession by said tripping devices, said lever carrying a needle projecting through a needle-tube extending from a plate of the movement through an aperture in the inner casing thereof, a spring projecting said needle, and means for adjusting said spring, substantially as described.

50 10. In a sphygmometric watch, the combination of a watch-movement, an apertured cap of the casing thereof, a lever pivotally secured to a plate of said movement and comprising an axis mounted in bearings on said plate, a long arm extending substantially at right angles to said axis and parallel to said plate, and a short arm extending outward from said axis, a series of tripping devices mounted on a wheel in the train of the watch-movement and adapted to engage the short arm, a needle carried by the long arm and projecting through said aperture, a spring projecting said needle, and means for adjusting said spring, substantially as described.

55 11. In a sphygmometric watch, the combination of a watch-movement, an apertured casing therefor, a lever pivotally secured on said movement and carrying a needle projecting through said aperture, an auxiliary wheel mounted on a wheel in the train of the watch-movement, a series of tripping devices, each provided with a radially-extending finger adapted to engage an arm of said lever and withdraw the needle, a spring for projecting said needle, and means for adjusting said spring, substantially as described.

60 12. In a sphygmometric watch, the combination of a watch-movement, an apertured inner casing therefor, a plate B, of the movement, correspondingly apertured, and a needle-tube extending between said apertures, a series of tripping devices carried by a wheel in the train of the watch-movement, a lever

pivotal secured on a plate of the movement, and having an arm engaged in succession by said tripping devices, said lever carrying a needle reciprocable in said tube, a spring projecting said needle, and means for adjusting said spring, substantially as described.

13. In a sphygmometric watch, the combination of a watch-movement, an apertured casing therefor, a tripping device carried by a wheel in the train of the movement, and a lever pivotally secured on said movement, and having one arm engaged periodically by said tripping device, said lever carrying a needle projecting through said aperture, substantially as described.

14. In a sphygmometric watch, the combination of a watch-movement, an apertured casing therefor, a tripping device carried by a wheel in the train of the movement, a lever pivotally secured on said movement, and having one arm engaged periodically by said tripping device, said lever carrying a needle projecting through said aperture, and a spring actuating said lever to project said needle, substantially as described.

15. In a sphygmometric watch, the combination of a watch-movement, an apertured casing therefor, a tripping device carried by a wheel in the train of the movement, a lever pivotally secured on said movement and having one arm engaged periodically by said tripping device, said lever carrying a needle projecting through said aperture, a spring actuating said lever to project said needle,

and means for adjusting said spring, substantially as described.

16. In a sphygmometric watch, the combination of the watch-movement, the auxiliary wheel II, the trip J, the lever K having the arms K² K³, the pulse-timing needle K K, the inner cap B and upper plate C, and the needle-tube between said cap and plate, substantially as described.

17. In a sphygmometric watch, the combination of a watch-movement, an apertured inner casing therefor, a tripping device carried by a wheel in the train of the movement, a needle projecting through the aperture in said casing, means for reciprocating said needle in said aperture, said means being engaged periodically by said tripping device to reciprocate the needle, substantially as described.

18. In a sphygmometric watch, the combination of a watch-movement, an apertured inner casing therefor, a tripping device carried by a wheel in the train of the movement, a needle projecting through the aperture in said casing, means for withdrawing said needle in said aperture, said means being engaged periodically by said tripping device, and a spring for projecting said needle, substantially as described.

ORSON H. WOODWORTH.
